COMBINED FLOOR WAXER AND POLISHER

William Henry Lee, Toronto, Ontario, Canada

Application December 22, 1932, Serial No. 648,483
In Canada November 17, 1932

8 Claims. (Cl. 91—39)

My invention relates to improvements in combined floor waxes and polishers, and the object of the invention is to provide a simple, cheap, light, easily and flexibly manipulated device which will provide means which will prevent the drying or hardening of the wax when the device is not in use and the consequent scraping or scratching of the floor surface when the waxer is again applied, in which a soft surface will be presented to the floor even after the wax supply in the waxer has become exhausted, in which a single unit is convertible to serve either as a container for the wax or as a polisher body and thus dispense with a separate polishing attachment, in which the operation of waxing or polishing may be performed on either horizontal or vertical surfaces and without kneeling or laborious effort to reach parts which are not easily accessible, which will readily adapt itself to follow uneven floor surfaces and which, when reciprocated over the floor surface, will tend to take a horizontal rotary movement over the surface similar to that employed during hand rubbing, and it consists essentially of the arrangement and construction of parts all as hereinafter more particularly explained.

Fig. 1 is a perspective view of my device attached to be used as a floor waxer.

Fig. 2 is a similar view showing my device attached for use as a floor polisher after the operation of waxing.

Fig. 3 is an enlarged perspective view of the device used as a polisher with the operating handle removed.

Fig. 4 is a longitudinal sectional view through Fig. 3.

Fig. 5 is a perspective detail of the waxer removed from the polishing body in which it is contained during the operation of polishing.

Fig. 6 is a perspective detail of the waxer with the outer fabric cover removed and showing the rubbing plate in its enclosed fabric envelope.

Fig. 7 is a perspective view of the rubbing plate removed from the envelope.

Fig. 8 is a cross sectional view through Fig. 4 on line 8—8.

Fig. 9 is a similar view to Fig. 8 showing the device applied to the nozzle of a suction machine so as to be operated by such machine instead of manually by the handle illustrated in Fig. 8.

Fig. 10 is a longitudinal sectional view through the device showing the waxer in its container and the body of the polishing member forming the cover for such container.

Fig. 11 is an enlarged perspective detail of the waxing element laid out flat.

Fig. 12 is a sectional view through the body of the container showing the fabric cover in position for receiving the waxing paste.

In the drawing like letters of reference indicate corresponding parts in each figure.

1 indicates the body of a container provided with a cover 2 in which the waxing element which I will now describe is contained.

3 is a rigid plate preferably formed of thin metal from which a lug 4 extends from its upper face longitudinally thereof, the lug 4 being provided with a small orifice 4^x. 5 is a fabric envelope in which a plate 3 is contained, the flaps 5^x and 5^y of the envelope forming a slotted opening through which the lug 4 of the plate 3 extends. The ends of the envelope are preferably formed by the turned over portions 6 and 7 which are sewn or otherwise suitably secured to the body of the envelope.

8 is a fabric bag forming an outer cover, the edge or mouth of the bag being formed with a seam 8^x through which an elastic 9 extends so as to draw the mouth together when in position over the envelope enclosed plate 3. In supplying the waxer with paste wax, the bag 8 is placed in the container body 1 in the position illustrated in Fig. 12, the edge or mouth of the bag being turned outward over the upper edge of the container so as to be resiliently held by the elastic edging 9.

The wax is then poured into the bag and spread in a layer 9^x. The plate 3 and its enclosing envelope 5, as illustrated in Fig. 6, is then placed in the bag upon the top of the wax and the elastic edge of the bag then released from the upper edge of the container 1 and passed over the top of the envelope 5 and its enclosed plate to assume the position shown in Fig. 5.

10 is an operating handle connected to the lug 4 by a universal joint connection comprising a stud 11 having a reduced threaded portion 12 which is passed through the orifice 4^x of the lug 4 and secured in position by a butterfly nut 13, the wings of the nut engaging the upper face of the envelope 5 and its contained plate so as to prevent the nut turning.

14 is a stud member which fits into a bore 15 in the end of the handle 10, the inner end of the stud 14 being formed into a spike 16, the sharpened end of which is driven into the base or end of the bore 15, such spike being rectangular prevents the turning of the stud in the bore. The outer end of the stud 14 is formed into a

tongue 17 which is pivotally connected between the jaws 11^x forming the outer end of the stud 11 by a transverse pin 18.

The operator grasps the handle 10 of the 5 waxer, the lower face of the waxer resting upon the floor, the universal joint between the handle and waxer permitting a free movement of the waxing element over the surface of the floor and so that it can assume either a horizontal or vertical position to operate on horizontal or vertical 10 surfaces and which may readily be passed into corners or under furniture or into any other confined space to spread the film of wax over the surface of the floor. When the wax has been 15 applied as above stated the waxer is placed in the container body 1 with the handle attached.

19 is a polishing element which is formed preferably of a strip of sheep skin with the woolly side of the skin presented outward to 20 contact with the floor. The ends of the strip 19 are provided with extensions 20 and 21 to the inner faces of which are attached thin rigid metal plates 22 by means of rivets 23 or any 25 other suitable means. The strip 19 is placed over the cover 2 of the container, the extensions 20 and 21 with the metal plates 22 are folded inward to contact with the inner face of the end walls of the cover.

The cover is then placed over the body 1 so 30 that the in-turned ends of the polishing element 19 are gripped between the end wall of the cover 2 and the end walls of the container body 1. It will, of course, be understood that the container cover 2 is made slightly longer than the 35 container body 1 so as to permit of the attachment of the polishing element as above described.

When the device is used as a polisher, the 40 container cover illustrated in Fig. 10 is removed and inverted and the container body 1 placed within the inverted container cover. When in this position or the position illustrated in Figs. 2, 3 and 4 with the waxing element inserted 45 therein, the polishing element may be moved over the surface of the floor in the same manner as that described in connection with the waxing, the movement of the polishing element being free and flexible so as to have not only reciprocating but a horizontal rotary movement similar to that which is employed by a person rubbing the floor manually and thus quickly and 50 efficiently polishing the surface of the floor, the container adding weight to aid in polishing. When the polishing operation is complete the 55 handle 10 is removed, the cover 2 being then removed from its inverted position and placed over the top of the wax container 1 thereby enclosing the waxer and preventing any drying of the wax through evaporation and the 60 consequent hardening of the same so that when the wax is again applied the wax will remain soft and free to spread over the surface of the floor without any tendency to scratch or otherwise damage the floor surface.

65 From the above description it will be seen that I have devised a device which will eliminate all necessity for kneeling and rubbing the floor manually, which will readily enter into the corners or under radiators or other room furniture so as to polish parts of the floor which 70 otherwise are not easily accessible and which is readily applicable to polish vertical surfaces such as wainscots and risers of stairways, which will readily follow the uneven surface of the 75 floor so that it will equally polish the whole sur-

face thereof, and which will always present a soft rubbing surface even when the wax contained in the waxer is practically used up, a fabric or felt envelope 5 preventing any contact of the hard plate 3 with the floor surface which 80 would tend to scratch or mar it.

It will also be understood that the waxer may be used either for spreading wax in paste form as above described, or for the spreading of liquid wax which is poured on the floor and then spread around by the waxer to distribute 85 evenly over the floor surface.

In Fig. 9, I have shown my waxer applied to the nozzle 24 of a suction machine. It will be noted in this figure that the nozzle only bears at its ends upon the waxer having an interspace which is sufficiently closed to the passage of air by the flaps 5^x and 5° to produce sufficient suction to hold the waxer to the nozzle and yet allow of a small quantity of air seeping through to pass to the suction machine motor through the duct 25 for the purpose of cooling the motor.

What I claim as my invention is:

1. A combined waxer and polisher comprising 100 a waxing element, a container body in which the waxing element freely fits to form an operating means for the polisher, a cover for the container in which when inverted the container body fits; and a polishing element extending 105 over the outer face of the inverted cover.

2. A combined waxer and polisher comprising 110 a container body to form an operating means for the polisher, a waxing element fitting within the body, a cover for the container, a polishing element extending over the upper face of the cover and engaged at its ends between the end walls of the container and cover and adapted when removed from the container body and in an inverted position to receive the container 115 body, and a detachable handle for the waxer.

3. A combined waxer and polisher comprising 120 a waxing element, a container body in which the waxing element freely fits to form an operating means for the polisher, a cover for the container body in which when inverted the container body fits, a polishing element extending over the outer face of the inverted cover, a handle, and a flexible connector for attachably connecting the handle to the waxing element.

4. In a floor waxer and polisher, a waxing element, a polishing element, and a closed container for the waxing element adapted when in the open position to receive the waxing element and to form a base for the polishing element operated by the waxing element.

5. In a floor waxer and polisher, a waxing element, a polishing element, a closed container for the waxing element adapted when in the open position to receive the waxing element and to form a base for the polishing element operated by the waxing element, and a handle attachable to the waxing element when the container is in the open position for polishing.

6. In a floor waxer and polisher, a waxing element comprising a plate having an upstanding portion having a transverse circular orifice extending therethrough, a stud turnable on a transverse axis within the orifice, a handle, and a hinge connection between the handle and stud having its axis at right angles to the axis of the stud.

7. In a floor waxer and polisher, the combination with the nozzle of a vacuum cleaner, of a 150

free plate, a lug extending from the plate longitudinally thereof and of the engaged nozzle, a fabric cover for the plate through which the aforesaid lug protrudes and extending between the edge of the nozzle and plate to form a suction seal, and means for retaining a charge of wax against the lower face of the plate.

5 8. In a combined floor waxer and polisher, a container body, an inverted cover for the body

in which such body fits, a polishing element extending over the outer face of the cover and having its ends extending over the end edges of the cover and inserted between the end walls of the cover and body, and a waxer fitting the container body to form an operating medium for the polisher.
